UNITED STATES PATENT OFFICE.

THOMAS WALKER, OF PHILADELPHIA, PENNSYLVANIA.

STUFFING-BOX.

SPECIFICATION forming part of Letters Patent No. 228,957, dated June 15, 1880.

Application filed April 26, 1880. (No model.)

To all whom it may concern:

Be it known that I, THOMAS WALKER, a citizen of the United States, residing in Philadelphia, Pennsylvania, have invented certain 5 Improvements in Stuffing-Boxes for Steam-Engines, of which the following is a specification.

The object of my invention is to make a metallic piston-rod packing which can be 10 easily applied to the tubular projection of the cover of a steam cylinder or pump after removing the usual follower or gland; a further object of my invention being the ready removal of the packing without detaching the cover 15 from the cylinder or pump; and a still further object is to prevent the leakage of steam between the packing-rings.

In the accompanying drawings, Figure 1, Sheet 1, is a vertical section of part of a cylinder-cover with my improved packing; Fig. 2, a sectional plan on the line 1 2; Fig. 3, a detached view of one of the packing-segments; and Fig. 4, Sheet 2, sections of the several parts of the packing detached from each other.

25 In Fig. 1 A represents part of the cover of a steam cylinder or pump, and *a* the usual tubular projection for receiving the ordinary gland or follower, which has been removed to make way for my improved packing. The 30 fixed part of this packing consists of the two annular plates B and C, the flanged sleeve D, and ring E, (best observed in Sheet 2,) the yielding part of the packing consisting of the three pairs G, G', and G'' of packing-rings which hug 35 the piston-rod, (shown by dotted lines in Fig. 1,) each ring being made preferably in three segments, the number of which, however, may be increased to an extent suggested by the diameter of the piston-rod.

40 It may be stated here that the number of pairs of rings may also be varied for a piston-rod of very small diameter. For instance, there may be but one pair of packing-rings, and for a rod of very large diameter it may be 45 advisable to use more than three pairs of rings.

The annular plate B is adapted to a recess in the top of the plate C, and when the former is fitted to the latter there is a chamber between them for the reception of the upper 50 pair of packing-rings. In like manner, when the flange of the sleeve D has been fitted into

a recess in the under side of the plate C there will be a chamber between the latter and a rib, *e*, in the sleeve, for the reception of the second pair of packing-rings, and a third chamber for a third pair of packing-rings, between the internal rib, *e*, of the sleeve D and the ring E, which is fitted to the said sleeve and secured thereto by lateral screws or otherwise. 55

The sleeve D and ring E fit snugly in the interior of the tubular projection of the cover A, the flange of the cover resting on the top of the said projection, and the stud-bolts *b*, which may have been used in securing the ordinary gland, serving to secure the new packing-place. 60

An important advantage of my invention is the facility with which the packing can be withdrawn when removal for any cause becomes necessary. 70

Many metallic packings are so constructed that their removal without first detaching the cover of the cylinder or pump is either difficult or impossible; but this is not the case 75 with my improved packing, for after detaching the nuts of the stud-bolts the annular plates B and C, with intervening packing-rings, can be withdrawn, and the remainder of the packing can then be raised from the interior of the 80 projection *a* with comparative ease.

As the several pairs of packing-rings are alike, a description of one pair only will suffice.

Each packing-ring is composed, in the present instance, of three segments, *w w w*, a perspective view of one of which is shown in Fig. 3, on reference to which it will be seen that each segment is provided with a spring, *m*. Each ring is, in the first instance, continuous, and at the three points where it has to be severed are bored three holes adapted to the three pins *y*, after which the ring is severed through the center of each hole, and the result will be three segments, in each end of each of which there is a semicircular recess. 90

In fitting the packing-rings to each chamber, first one set of three segments is placed in the bottom of the said chamber, the pins *y* being introduced into their places between the segments, after which a second set of three 100 segments is placed in the chamber on the first, one of the segments of one set having an ori-

fice for receiving a steady-pin projecting from one of the segments of the other set, so that the relative circumferential position of the segments of the two rings can never be changed, 5 this relative position being such that the ends of the segments of one set shall be midway, or thereabout, between the ends of the segments of the other set, thereby breaking joints.

The segments are so made that when three 10 are fitted together to form a ring the space within the ring will be somewhat less in diameter than the piston-rod when the latter is absent; hence, when the said rod is in place there will be a continuous tendency of each 15 ring, owing to the springs of the segments, to hug the piston-rod.

The object of the pins introduced between the segments is twofold. They act as steady-pins to maintain the segments in their proper 20 relative position; but their most important object is to bridge the spaces between the said segments and prevent leakage, for whatever may be the extent of these spaces the pressure of such steam as may possibly gain access to 25 the interior of the ring will be exerted against the pins *y*, and the latter, seeking a bearing against the segments, will necessarily close the spaces.

I claim as my invention—

30 1. The combination, in a piston-rod packing, of ring-segments, each having a spring at the back and a semicircular recess in each end, with cylindrical pins *y* interposed between

the recessed ends of adjoining segments, said pins being as long as the segments are thick, 35 all substantially as set forth.

2. The combination of the tubular projection *a*, the flanged sleeve *D*, having one or more sets of packing-rings, and the detachable annular plate *B*, having a series of packing-rings 40 independent of those of the sleeve *D*, as set forth.

3. The combination of the tubular projection *a*, the flanged sleeve *D*, having an internal rib, *e*, the two sets of packing-rings *G'* *G²*, the 45 ring *E*, for confining the set of rings *G²*, and the annular plate *C*, for confining the set of rings *G'* to the sleeve *D*, and the latter to the projection *a*, as set forth.

4. The combination of the tubular projection 50 *a*, the stud-bolts *b*, the flanged sleeve *D*, adapted to projection *a*, and having one or more pairs of packing-rings, the annular plate *B*, having an independent set of packing-rings, and the annular plate *C*, having in one side a recess 55 for the reception of the flanged end of the sleeve *D*, and in the other side a recess for the reception of the plate *B*, as specified.

In testimony whereof I have signed my name to this specification in the presence of 60 two subscribing witnesses.

THOMAS WALKER.
